CLAIM

The ornamental design for a display screen with animated graphical user interface, as shown and described.

DESCRIPTION

FIG. 1 is the first image in a sequence for a display screen with animated graphical user interface showing our new design;

FIG. 2 is the second image thereof;

FIG. 3 is the third image thereof;

FIG. 4 is the fourth image thereof;

FIG. 5 is the fifth image thereof;

FIGS. 6–10 are a sequence for a display screen with animated graphical user interface showing an alternative embodiment thereof; and,

FIGS. 11–15 are a sequence for a display screen with animated graphical user interface showing an alternative embodiment thereof.

The appearance of the animated graphical user interface sequentially transitions between the images shown in FIGS. 1–5, 6–10, and 11–15. The process or period in which one image transitions to another forms no part of the claimed design. The broken line showing of the display screen, text, and other graphic features forms no part of the claimed design. The broken line showing of an electronic device illustrates environmental structure and forms no part of the claimed design.
